(57) **CLAIM**

The ornamental design for a hinged spiral coil aglet, as shown and described.

DESCRIPTION

FIG. 1 is a perspective view of a hinged spiral coil aglet showing my new design;

FIG. 2 is another perspective view thereof;

FIG. 3 is another perspective view thereof;

FIG. 4 is a front view thereof;

FIG. 5 is a back view thereof;

FIG. 6 is a top thereof; and,

FIG. 7 is a bottom view thereof;

FIG. 8 is a left side view thereof;

FIG. 9 is a right side view thereof;

FIG. 10 is another perspective view thereof with the coil extended;

FIG. 11 is another perspective view thereof with the coil retracted;

FIG. 12 is a further perspective view thereof with a string partially wrapped;

FIG. 13 is a further perspective view thereof with a string fully wrapped;

FIG. 14 is a further perspective view thereof with the wrapped coil retracted; and,

FIG. 15 is a further perspective view thereof with the wrapped coil retracted.

The broken lines showing the string and the coil attachment are for the purpose of illustrating environmental structure and form no part of the claimed design.
